(57) CLAIM

The ornamental design for a bandage clip, as shown and described.

DESCRIPTION

FIG. 1 is a perspective view of a bandage clip;

FIG. 2 is a side view thereof;

FIG. 3 is a side view thereof;

FIG. 4 is a front view thereof;

FIG. 5 is a back view thereof;

FIG. 6 is a top view thereof; and,

FIG. 7 is a bottom view thereof.

The broken lines shown in FIGS. 1-7 illustrate portions of the bandage clip that form no part of the claimed design.
